UNITED STATES PATENT OFFICE.

MICHAEL JOHN DUFF, OF BRIDGEPORT, CONNECTICUT.

DESIGN FOR A DOLL.

Application filed November 4, 1922. Serial No. 4,220. Term of patent 3½ years.

To all whom it may concern:

Be it known that I, MICHAEL JOHN DUFF, a subject of the King of Great Britain, residing at Bridgeport, in the county of Fairfield and State of Connecticut, have invented a new, original, and ornamental Design for a Doll, of which the following is a specification, reference being had to the accompanying drawing, forming part thereof.

Fig. 1 is a front elevational view of the doll;

Fig. 2 is a rear elevational view thereof; and

Fig. 3 is a side elevational view thereof.

I claim:

The ornamental design for a doll, as shown.

MICHAEL JOHN DUFF.
